COMBINED FEEDING SPOON AND MASK

John L. Wertz, Detroit, Mich.

Application December 20, 1956, Serial No. 44,293

Term of patent 14 years

(Cl. D44—29)

Fig. 1

Fig. 3

Fig. 1 is a front view, in perspective, of a combined feeding spoon and mask embodying my design.

Fig. 2 is a side view thereof.

Fig. 3 is a vertical sectional view through the center of Fig. 1.

I claim:

The ornamental design for a combined feeding spoon and mask, as shown.
